UNITED STATES PATENT OFFICE.

EDWARD C. STEARNS, OF SYRACUSE, NEW YORK.

DESIGN FOR A BICYCLE-FRAME.

SPECIFICATION forming part of Design No. 30,245, dated February 21, 1899.

Application filed May 9, 1898. Serial No. 680,229. Term of patent 7 years.

To all whom it may concern:

Be it known that I, EDWARD C. STEARNS, a citizen of the United States, residing at Syracuse, in the county of Onondaga and State of New York, have invented and produced a new and original Design for Bicycle-Frames, of which the following is a specification, reference being had to the accompanying drawings, forming part thereof.

10 Figure I shows in perspective the frame of a bicycle constructed according to my design. Fig. II is a cross-section taken through the lower rear-fork sides, showing their peculiar construction.

15 My design relates to a new form of bicycle-frame, of which the essential features are the lower rear-fork sides, constructed, as here shown, of elliptical form in cross-section, arranged with their longest diameter vertical

20 and their shortest horizontal. Of these the left extends rearwardly from the crank-hanger with a uniform inclination, while the right for a short distance extends rearwardly from the crank-hanger substantially at right

25 angles, where the two fork sides are connected by a brace or bridge a short distance from the crank-hanger and parallel thereto. Just rearwardly of this bridge the right fork side is bent outwardly in a curve, substantially as

30 here shown, the remainder of the fork side extending rearwardly with a slight outward inclination.

The various parts are indicated in the drawings by reference-numerals as follows:

1 indicates the crank-hanger, and 2 and 3, 35 respectively, the lower rear-fork sides extending rearwardly from the crank-hanger at a slight angle. These tubes also gradually taper in the vertical plane, gradually diminishing from front to rear. One of them, the 40 right, as here shown, is formed with a member 4, arranged substantially at right angles to the crank-hanger, with an inclined member 5, and with an outward curve 6, connecting these two members. A bridge 7 connects the 45 two fork sides, being arranged substantially at right angles to the crank-hanger and just within said curve.

The upper rear-fork sides 8 8 are formed as here shown. At about the point 9 they are 50 connected to the main upright or seat-post-truss tube 10, from which they incline downwardly and slightly outwardly to about the points 11 11, where is arranged between them the brace or bridge 12. At this point each 55 tube is bent, so that for the rest of its extent its outward inclination is more gradual and very slight.

What I claim is—

The design for a bicycle-frame, substantially as shown and described.

In testimony whereof I have hereunto signed my name.

EDWARD C. STEARNS. [L. S.]
